FILLER FEED CONTROL MECHANISM FOR
CIGAR MACHINES

Sigurd Clausen, Brooklyn, and Joseph A. Neumair, Hollis, N. Y., assignors to International Cigar Machinery Co., a corporation of New Jersey

Application November 18, 1949, Serial No. 128,076

12 Claims. (Cl. 131—21)

1

This invention relates to tobacco feeds for cigar machines and particularly to controls for such feeds where a predetermined length of a stream of tobacco is fed to a measuring chamber by means of intermittently moving conveyor belts that form the channel of the cross feed, the channel usually consisting of two side belts and a bottom belt.

It is an object of this invention to attain greater uniformity of bunch lengths by a more accurate method of producing uniform charge lengths. The cross feed methods employed heretofore resulted in occasional short or long charge lengths which produced inferior bunch lengths or seconds. The former methods employed a reciprocating cam lever drive. When there was a greater (or less) than normal resistance in the cross feed conveyor, said lever and its intermediate linkages yielded in such a fashion that a short or long charge length resulted. In order to overcome this, it is an object of this invention to devise a crank or rotary motion for the reciprocating motion heretofore employed. By employing a crank-like motion the length of the feeding stroke becomes a function of diameter or center to center distance which does not vary materially as a result of stresses or strains or "play" in the linkages.

It is a further object of this invention to employ suitable means for maintaining this more accurate feed achieved by the rotary motion. The natural tendency of the belt to relieve itself of the stress imposed upon it during the forward feeding motion causes a slight backward movement when said belt comes to rest. This tends to vary the length of the subsequent charge. It is therefore a further object of this invention to employ means whereby the drive pulley of the conveyor is maintained against the tension of the belt in the exact position at which it stopped. Thus uniformity in charge length is maintained.

Another object of this invention is to accurately synchronize the movements of the driving means with the movements of the arresting means.

Still another object of this invention is to provide a suitable means for omitting or skipping the charge feed when there is a sufficient height of charge lengths in the charge storage chamber as measured by the charge storage plunger.

Still another object is to engage the feed pawls while they are at rest to prevent a jerking motion and lessen wear and/or breakage of the pawls and ratchet wheel.

With these and other objects not specifically mentioned in view the invention consists in certain constructions and combinations which will be hereinafter fully described.

In the accompanying drawings, which form a

2

part of this specification and in which like characters of reference indicate the same or like parts:

Fig. 1 is a side elevation of the invention and contiguous parts of a cigar machine;

Fig. 2 is a partial end elevation taken on line 2—2 of Fig. 1;

Fig. 3 is a sectional end elevation taken on line 3—3 of Fig. 1;

Fig. 4 is a partial end elevation of the feeding pawl arrangement taken on line 4—4 of Fig. 1; and

Fig. 5 is a partial plan view taken on line 5—5 of Fig. 1.

With reference to Fig. 1, the bottom belt 12 of the cross feed channel C is supported on a plate 14 secured to the top portion of a suitable frame 16. Said belt is driven intermittently by means of a pulley 18 and is guided over suitable idler rollers 20. Pulley 18 is mounted on a horizontal drive shaft 22 which is supported in suitable bearings of frame 16. Also secured to shaft 22 is a ratchet wheel 24 (Figs. 1 and 2) which is intermittently rotated through the engagement of one of pawls 26 (Figs. 1 and 4) which are pivotally mounted on a stud 28 secured in the free end of an arm 30 of a bell crank lever 32 loosely mounted on shaft 22. Bell crank lever 32 also has two other integral arms 34 and 36.

The free end of arm 34 supports post 38 to which are anchored tension springs 40 to hold pawls 26 in engagement with ratchet wheel 24 during the feeding operation. Pivots connected to the free end of arm 36 is one end of an adjustable connecting rod 44, while the other end 46 of said rod 44 is pivoted to a bushing 48 which surrounds a sleeve 50 encircling a stud 52 which is an integral part and projects from a T-shaped block 54. The latter is slidably mounted in a slot 56 of the crank lever arm 58 which is rigidly secured to a gear 60 loosely mounted on a stud 62 held by a suitable lug on the main frame of the cigar machine (not shown). Member 54 is clamped to crank lever arm 58 by means

of a nut 64 that holds sleeve 50 against a spacer washer 66 which in turn transmits the clamping action of said nut onto the front face of crank arm 58, while the rear face of the latter is engaged by the flanged head end 68 of block 54, thus forming a rigid crank pin to which the lower end 46 of connecting rod 44 is pivoted at bushing 48. The lower end 46 of connecting rod 44, of course, is slightly narrower than sleeve 50 so that it may rotate freely on bushing 48.

Block 54 is also provided with a vertical threaded hole which engages with a vertical spindle 70, the bottom portion of which is loosely mounted in suitable bearings of lever 58, while the top portion of said spindle is supported by and projects from a cap 72 secured to the free

end of the spindle 70.

end of crank lever 58. The projecting end of spindle 70 carries a knurled knob 74 which permits turning of said spindle after loosening nut 64 of stud 52, which will effect an up or down movement of block 54 in slot 56 of crank arm 58. The type of mounting as described and as shown in Fig. 3, insures that member 54 will be rigidly secured to crank lever arm 58 without exerting any strain on screw 70 which provides a means for making fine adjustments.

Referring to Fig. 1, the various parts as shown are in a position ready to feed a predetermined length of the tobacco ribbon onto a suitable platform 300 above a storage or measuring chamber M. Said feeding commences when the gear 60 is rotated by a gear segment 76 secured to a shaft 78 which in turn is actuated by means of a cam lever 80 mounted on said shaft 78. Cam lever 80 in its free end carries a cam roller 82 engaging a cam track 84 of a cam 86 secured to a shaft 88 which is driven continuously in timed relation with the cigar machine.

Since pawls 26 on arm 30 at that moment are in engagement with the teeth of ratchet wheel 24, counter-clockwise rotation of gear 60 causes 25 ratchet wheel to rotate in a clockwise direction which, through shaft 22 and pulley 18, effects a feed movement of belt 12 in the direction of the arrow shown in Fig. 1. The length of tobacco charge fed onto the platform 300, of course, is determined by the stroke of the connecting rod 44. Said stroke may be varied by loosening nut 64 and turning knob 74 to adjust member 54 closer or further away from shaft 62 to provide a shorter or longer stroke as desired. Nut 64 is then tightened to secure the selected setting.

Double lever 96 pivoted on a stud 98 of frame 16 carries a pin 92 mounted on one arm 94. Pivoted to the other arm 102 by pin 100 is a link 104 whose other end is provided with a slot 106 40 engaging pin 108 on one end of release arm 110 pivoted in a horizontal portion of a feed pawl disengaging arm 114.

Arm 114 is loosely mounted on a stud 116 of frame 16. The other end of release arm 110 carries a pin 118 which protrudes through a hole 120 piercing each of a plurality of locking pawls 122 which are also pivoted on stud 116. Conveniently, a spacer 123 (Fig. 5) is provided to separate lock pawls 122 from feed pawl disengaging arm 114.

In operation, as connecting rod 44 nears the end of its feed stroke, a pin 90 mounted in the hub of double lever 32 contacts a pin 92 of arm 94, thereby rotating double lever 96. This causes link 104 to rise, releasing arm 110 which then permits locking pawls 122 to fall into engagement with ratchet wheel 24. This, of course, arrests the belts of the cross feed channel and also prevents the natural elasticity of the belt to move it slightly backward when the forward strain is released. Thus, variations in the subsequent lengths of tobacco charges fed over platform 300 are prevented and the uniformity of the predetermined charge lengths of each feeding operation are assured. Pawls 122 are slightly staggered for the purpose of quickly engaging the ratchet wheel 24 at the end of the feed stroke, i. e., one of the pawls is always in line with the teeth of the ratchet wheel.

Double lever 96 also has another arm 124, the end of which carries a square pin 126 (Figs. 1 and 2). As shown in Fig. 1, one face of the square pin is resting against a pin 128 which is 75

held in frame 16. When, at the end of the feed stroke, double lever 96 assumes the position described above, pin 126 moves away from pin 128 and a lock arm 130 swings about a stud 132 until the bottom face of lock arm 130 contacts pin 128 and the end face of said lock arm comes to rest directly behind square pin 126. Lock arm 130 is actuated at this time by means of tension spring 134 connected thereon by means of a post 136 carried by said arm 130. The other end of said spring is anchored to a post 138 held in frame 16.

At the finish of the feed stroke double lever 32 and the therewith connected mechanisms dwell. During this dwell, a toggle mechanism P actuates a horizontal pressure foot 144 which bears down upon the ribbon-like stream of tobacco in the cross feed channel C while at the same time the horizontal platform 300, which covers the measuring chamber M and upon which the predetermined length of tobacco ribbon was fed, is moved out of the way to permit a downward moving corrugated cutter 146 to sever the predetermined charge length of the tobacco ribbon T. A descending measuring plunger 148, slightly trailing behind said cutter 146 pushes the severed length of tobacco into the storage measuring chamber M. The horizontal pressure foot 144 mentioned above is secured to the bottom portion of a vertical shaft 142 to which is mounted a lug 140. To the latter is pivoted the abovementioned toggle mechanism P which through a link 141 is actuated by a suitable operating mechanism (not shown) of the cigar machine. The toggle mechanism P, the pressure foot 144, the corrugated cutter 146 as well as the measuring plunger 148, platform 300 and the measuring chamber M are of identical construction as the ones shown and described in Durning Patent 2,470,766, and therefore need not be further described.

To lug 140, which is similar to the [lug] 238 in said Durning Patent 2,470,766, is secured a plate 150 to which is pivotally mounted one end of an adjustable rod 152, while the other end of said rod is loosely mounted to the end of feed pawl disengaging arm 114. As lug 140 descends, rod 152 makes arm 114 swing about stud 116 so that a cam portion 154, at the opposite end of arm 114, is in the path of a feed pawl disengaging pin 156. Since arm 110 is pivotally mounted on pawl disengaging arm 114, link 104 is provided with a slot 106 to permit arm 110 to move freely in said slot when rod 152 rocks arm 114 about stud 116. Just prior to the full descent of measuring plunger 148, cam 86 and the linkages previously described, cause double lever 32 to return to its starting position. During the return motion of the latter, pin 156, which is mounted in a U-shaped member 158 and passes through a hole 160 in each of the pawls 26, contacts the curved cam portion 154 of arm 114 and raises pawls 26 out of engagement with ratchet wheel 24. Member 158 is loosely supported by stud 28 which is carried by arm 30 of lever 32. Since U-shaped member 158 is pivotally mounted, the raising of pawls 26 upon the return stroke when pin 156 rides up on the cam portion 154 of arm 114, causes said member to swing in such a manner as to effect an engagement of the bridge portion 159 of U-shaped member with a lock finger 161. The latter is employed for the purpose of keeping the pawls 26 out of contact with the ratchet wheel 24, thus eliminating undesired wear and noise. Lock finger 161 is pivoted on a pin 162

held by a suitable boss of arm 30 and is provided with a spring 164 suitably supported in arm 30 and acting upon finger 161. To the latter is also secured a control plate 192 which projects from finger 161 and which is employed for the purpose of effecting the release of U-shaped member 158 from lock finger 161 and consequently permitting pawls 26 to re-engage the ratchet wheel 24 when pawls 26 reach the end of their return stroke, thus making them ready for the next feed stroke in the following cycle of the machine. The disengagement of lock finger 161 from member 158 is caused when control plate 192 rides upon and contacts an L-shaped member 190 when arm 30 and pawls 26 reach the end of their return stroke. The L-shaped member 190 is carried by the arm 94 and extends into the path of plate 192 when returning with arm 30.

However, if a sufficient amount of tobacco is in the measuring chamber M, the L-shaped member 190 is held out of the path of control plate 192 and lock finger 161 is not tripped but stays in engagement with U-shaped member 158 which in turn causes pawls 26 to stay in raised position and out of engagement with ratchet wheel 24 so that during the next feed stroke imposed upon arm 30 the ratchet wheel 24 is not actuated and the cross feed remains arrested and no tobacco is fed onto the platform 300 during that cycle at the end of which the lock finger 161 may or may not be tripped, depending on the amount of tobacco in the measuring chamber.

The amount or height of the tobacco column in the chamber M (Fig. 1) is measured or tested by the vertically reciprocating measuring plunger 148 which is secured to the bottom end of a vertical spring mounted and cam operated shaft 166 which is of the same construction and operated in the same manner as the one disclosed in Durning Patent 2,470,766. The height of the tobacco column in the chamber M determines the vertical distance of the downward movement of plunger 148 and shaft 166, i. e., if the tobacco column is high, the plunger is arrested at a higher level, if there is little tobacco in the chamber the plunger descends to a much lower level.

To transmit the findings of plunger 148 to the cross feed control mentioned above, the shaft 166 carries a lug 168 to which is secured an adjustable trip screw 170 which is so set that normally during the end portion of the downward movement of plunger 148, it contacts the free end of an arm 172 and presses the same downward when the tobacco column is low. However, screw 170 is set in such a manner that it will not contact arm 172 when the tobacco column is high and it is therefore undesirable to feed more tobacco during the next cycle.

Arm 172 is pivoted on a stud 174 (Fig. 1) held by a suitable frame 176. The latter provides also the support for vertical shaft 142, cutter 146 and shaft 166 and is of identical design as the one disclosed in the aforementioned Durning patent. Arm 172 rests freely on the upper end of an adjustable vertical rod 178 which, at its lower end, is pivoted to a stud 180 carried by one end of lock arm 130.

As before mentioned, the tension spring 134 attached to lock arm 130 has the tendency to raise the right side of the latter, to which rod 178 is pivoted, and/or to lower the left or locking end. The downward position of said locking end of arm 130 is checked by either the square pin 126 carried by arm 124 or the stop pin 128 projecting from frame 16.

The control of the feed mechanism, i. e., keeping pawls 26 out of engagement with ratchet wheel 24 to stop the feed for the next cycle or cause a re-engagement to effect the feeding of tobacco, is determined by the position of the lock end of arm 130 and operates as follows: The pin 90 projecting from the hub of the double lever 32 describes an arc in the direction of the arrow in Fig. 1 during the forward or feeding stroke of said lever and contacts the pin 92 and depresses arm 94 to which pin 92 is mounted. The depressing or swinging of arm 94 also causes a swinging of arm 124 and thereby causing a disengagement of the square pin 126 from the lower edge of the locking end of arm 130 which, due to the action of tension spring 134, will be forced downward onto stop pin 128.

When, during the return stroke of double lever 32 the pin 90 releases the pin 92 and therefore arm 94, the square pin 126 on arm 124, due to the action of tension spring 182 has the tendency to return to its original position, but, since the locking end of arm 130 is now in a lower position, the square pin 126 is stopped by and comes to rest on the end edge of the locking end of arm 130. This, of course, will stop arm 94 in a more forward position, and consequently the L-shaped member 190 in a more downward position which holds the latter out of the path of the returning control plate 192 on lock finger 161.

However, shortly before pawls 26 on arm 30 of lever 32 return to their original position, plunger 148 enters the measuring chamber M and, as explained heretofore, depending on the height of the column of tobacco in the chamber the tripping screw 170 does or does not depress arm 172. If there is sufficient tobacco in the chamber, screw 170 does not depress arm 172 and therefore the position of lock arm 130 is not changed and arm 94 and L-shaped member 190 also remain in an unchanged position. With member 190 out of the path of control plate 192, the U-shaped member 158 upon reaching the end of the return stroke stays locked to finger 161 and the pawls 26 remain in raised position during the next forward or feed stroke of arm 30. Therefore, the mechanisms are arrested and no tobacco is fed during the next cycle.

However, if the tobacco is lower in chamber M the measuring plunger descends so that trip screw 170 contacts and depresses arm 172. Vertical rod 178 then moves downward and the locking end of arm 130 is raised and disengaged from the square pin 126. Tension spring 182 then swings lever 96 backward until the square pin 126 comes to rest on stop pin 128. L-shaped member 190 is then in the path of the returning control plate 192. As the latter reaches the end of the stroke it contacts and rides onto said L-shaped member and effects a disengagement of lock finger 161 from U-shaped member 158 which in turn permits the pawls 26 to engage the ratchet wheel 24 to feed tobacco during the next cycle.

When, during the upward movement of plunger 148 the trip screw 170 disengages from arm 172 the action of spring 134 upon arm 130 has the tendency to move the locking end of said arm downward to its original position, but since the square pin 126 on arm 124 has moved backward, the lower edge of the locking end of arm 130 comes to rest on said square pin 126 where it remains until during the feeding cycle double lever 96 is moved forward as a result of the action of pin 90 on pin 92.

Secured in a conventional manner to the rear

of ratchet wheel 24 is a gear 194 which drives a gear 196 secured to a shaft 198 loosely supported in suitable bearings of frame 16. Also secured to shaft 198 are two bevel gears 200 each of which meshes with a bevel gear 202 each of which is mounted on a vertical shaft 204. The upper end of each shaft carries a pulley (not shown) both of which drive the customary side belts of the cross feed channel C in synchronism with the bottom belt 12.

In view of the foregoing, it will be evident that the crank motion for feeding insures that any play between segment 76 and gear 60, or any spring in segment 76 that might cause undesired rotation of gear 60 will not appreciably affect the length of tobacco fed.

The invention above described may be varied in construction within the scope of the appended claims.

We claim:

1. In a mechanism for feeding charge lengths of tobacco in a cigar machine, a horizontal conveyor belt; a plurality of pulleys; a large driven pulley engaging said conveyor belt; circumferential ratchet teeth on said pulley; a lever fulcrumed at the axis of said pulley; a plurality of pawls operatively mounted on one end of said lever to engage said ratchet teeth to drive said pulley; a gear crank; means adjustable on said crank to vary the effective radius of said gear crank; a connecting rod between said gear crank and said lever to move said lever through a distance equal to the throw of said gear crank; a second lever; a moving cam; a cam follower on said second lever engaging said cam, so that a reciprocatory movement is imparted to said second lever; a gear section on the other end of said second lever engaging said gear crank so that the reciprocatory movement of said second lever is transformed into rotary motion at said gear crank; means for disengaging said pawls from the said teeth on the return stroke; and a plurality of locking pawls to maintain said driven pulley relatively stationary during the return stroke of the feed pawls.

2. In a mechanism for feeding charge lengths of tobacco in a cigar machine, a horizontal conveyor belt; a driven pulley engaging said conveyor belt; circumferential ratchet teeth on said pulley; a pivoted lever; a pawl operatively mounted at one end of said lever to engage said ratchet teeth; a gear crank; means adjustable on said crank to vary the effective radius of said gear crank; a connecting rod between said gear crank and said lever; and a second lever comprising, at one end, a cam follower engaging a cam so as to impart a reciprocatory movement to said second lever and, at the other end, a gear section engaging said gear crank so that the reciprocatory movement of said second lever is transformed into a rotary motion at said gear crank to ultimately impart intermittent motion to said driven pulley.

3. In an intermittent feed conveyor mechanism comprising a conveyor belt mounted on idler pulleys; a driven pulley engaging said conveyor belt; circumferential ratchet teeth on said driven pulley; a pivoted lever; a plurality of pawls on one end of said lever mounted so that at least one of said pawls will operatively engage said ratchet teeth to drive said pulley; a gear crank; means adjustable to vary the length of the crank arm of said gear crank; a connecting rod from said lever to said gear crank; a reciprocating cam lever, comprising a cam follower at one end

and a gear section on the other end to engage said gear crank and impart rotary motion thereto so that the length of the stroke of said connecting rod intermittently driving said driven pulley is established by the length of the adjustable crank arm of said gear crank; and means for holding said driven pulley against backward rotation during the recovery movement of said operating pawls.

4. In a mechanism for intermittent feeding by a conveyor belt in a cigar machine, a cam operated reciprocating lever; a gear section on the operative end of said lever; a gear crank engaging said gear section so that the reciprocatory motion of said lever is transformed into rotary motion at said gear crank; means to vary the length of the arm of said gear crank; a driven pulley engaging said conveyor belt; and a reciprocating member operatively connecting said

20 crank gear to said driven pulley to advance said pulley a predetermined degree on the drive stroke of said reciprocating lever.

5. An intermittent conveyor feed belt mechanism feeding charges to the storage chamber of a cigar machine, comprising a conveyor belt; a driven pulley engaging said conveyor belt; circumferential ratchet teeth on said pulley; a primary plurality of pawls staggered so that one of said pawls operatively engages said ratchet teeth; said primary pawls to intermittently drive said pulley in one direction; a rocker to disengage said pawls at the completion of the driving stroke; a lock to maintain said pawl in disengagement, a trip member to open said lock to permit re-engagement of the pawl, said trip member being intermediately connected to the measuring plunger of the storage chamber of the cigar machine so that said trip member is out of operative position when the storage chamber of said cigar machine is filled; a second plurality of pawls staggered so that one of said pawls operatively engages said ratchet teeth to hold said driven pulley against backward motion when said primary pawls are disengaged, and a link from said trip member to said second-named pawls operative to move said second-named pawls out of locking position when said trip member is in tripping position and into locking position when said trip member is out of operative position whereby one set of pawls is not in engagement when the other set is.

6. An intermittent conveyor feed belt mechanism feeding charges to the storage chamber of a cigar machine, comprising a conveyor belt; a driven pulley engaging said conveyor belt; circumferential ratchet teeth on said pulley; a primary plurality of pawls staggered so that one of said pawls operatively engages said ratchet teeth; a gear crank operatively attached to said primary pawls to intermittently drive said pulley in one direction; adjustment means on said gear crank to vary the length of its crank arm; a rocker to disengage said pawls at the completion of the driving stroke; a lock to maintain said pawl in disengagement, and a trip member to open said lock to permit re-engagement of the pawl, said trip member being intermediately connected to the measuring plunger of the storage chamber of the cigar machine so that said trip member is out of operative position when the storage chamber of said cigar machine is filled.

7. A method of intermittently advancing a feed conveyor belt in a cigar machine a predetermined distance wherein reciprocatory drive is taken from an adjustable rotary crank move-

ment so that mechanical inaccuracies resulting from wear between articular members of the mechanism may be compensated for by adjusting the length of the crank, and backward motion of said conveyor belt is positively prevented during the intervals between intermittent advancement of said conveyor belt.

3. The method of controlling the feed stroke in an intermittent feed conveyor mechanism in a cigar machine wherein a constant reciprocatory drive is transformed into positive rotary drive and then back to reciprocating drive and controlling the length of stroke of said second-mentioned reciprocating drive by varying the radius of said rotary drive.

9. In a cigar machine having an intermittent feed belt, a pulley to drive said belt, circumferential ratchet teeth on said pulley, a storage chamber to receive material from said feed belt, a measuring plunger movable into said chamber to test the amount of material therein, a reciprocating drive pawl operative to engage the ratchet teeth on said pulley to move it in one feed direction, means to lift said drive pawl from said ratchet teeth at the end of the feed movement, a latch to hold said pawl in lifted position during its return movement, a lock pawl movable to engage said ratchet teeth to hold the drive pulley against backward motion, and a member operative at the end of the feed stroke to move said locking pawls to engage said ratchet teeth, a mechanism connected to said measuring plunger and movable therewith, a trip on said mechanism operative in selected position of said measuring plunger to trip said latch on said drive pawls, and a link secured to said mechanism and to said lock pawls operative to lift said lock pawls when said trip is in tripping position whereby said lock pawls will be out of operative engagement when said drive pawls are in operative engagement with said pulley.

10. A mechanism for intermittent advancement of a feeder conveyor belt in a cigar machine, comprising a driven pulley operatively engaging said conveyor belt, circumferential ratchet teeth on said driven pulley, a lever pivoted coaxially with said driven pulley, means to reciprocate said lever in a forward feed movement and a backward recovery movement, a drive pawl on the free end of said lever operative to engage said ratchet teeth to drive said pulley in one direction, lifting means to raise said drive pawl from said ratchet teeth at the end of the feed movement of said lever, a latch to hold said pawl out of engagement with said ratchet teeth during the recovery movement of said lever, a trip for selectively disengaging said latch at the end of the recovery movement when another feed movement is desired, a locking pawl mounted to engage said ratchet teeth during the recovery movement of said feed pawl, a device to lift said locking pawl during the feed movement of said lever, said device comprising a lever mounted on an upwardly movable fulcrum, a link connecting said fulcrum to said drive pawl lifting means, one end of said lever engaging said locking pawl to lift it, a link running from the other end of said lever to said trip so that when said trip is in tripping position said other end of said lever will be raised and when said trip is in non-tripping position said other end of said lever will be lowered a greater distance than the lifting distance of said fulcrum by said drive pawl lifting means whereby the locking pawls will always be

in engagement when the drive pawls are out of engagement.

11. In a mechanism for intermittently advancing a feed conveyor belt in a cigar machine, a driven pulley engaging said conveyor belt, circumferential ratchet teeth on said pulley, a pivoted lever, drive pawls operatively mounted on the free end of said lever to engage said ratchet teeth to drive said pulley, means to move said pawls out of operative position at the end of a feed stroke, a latch to lock said pawls out of operative position, trip means movable to tripping and non-tripping position at the beginning of said feed stroke to trip said latch to release said drive pawls into operative position when desired, locking pawls to engage and hold said pulley against backward movement, members secured to said trip means to lift said locking pawls out of locking position when said trip means is in tripping position to release said drive pawls when a feed stroke is desired and to leave said locking pawls in engagement when a feed stroke is omitted.

12. An intermittent conveyor feed belt mechanism for forwarding charges of predetermined length to a storage chamber; a measuring plunger mounted for movement into said storage chamber to measure the amount of charges stored therein; means to sever a charge length fed from the forward end of said belt, said feed belt mechanism comprising a conveyor belt, a driven pulley engaging said conveyor belt, circumferential ratchet teeth on said pulley, a primary plurality of pawls mounted to operatively engage said ratchet teeth; an oscillating drive supporting said primary pawls to intermittently drive said pawls in one direction; a rocker cam member to disengage said pawls at the completion of the driving stroke; said rocker cam being connected to said measuring plunger and rocked therefrom; a lock to maintain said primary pawls in disengagement; a movable trip member to open said lock to permit re-engagement of the pawls, a link connecting said trip member to the measuring plunger of the storage chamber so that the trip is moved out of operative position when the height of charges in said storage chamber exceeds a predetermined amount; and a second plurality of staggered pawls pivoted on said rocker cam member so that one of said pawls may operatively engage said ratchet teeth as said rocker cam member disengages said primary pawls to hold said driven pulley against backward motion when said primary pawls are disengaged, and a link from said trip member to said second-named pawls to hold said second-named pawls in engagement with said ratchet teeth against the movement of said rocker cam member when said trip member is in non-tripping position and to permit said rocker to lift said second-named pawls out of engaging position when said tripping member is in tripping position.

SIGURD CLAUSEN.
JOSEPH A. NEUMAIR.
